D. DEWEY.
CLOTH SHEARING MACHINE.

Patented June 27, 1809.

David Dewey.

1083X

Letters Patent.

Signed June 27, 1804.

The Schedule referred to in these Letters Patent and making part of the same, containing a description in the words of the said David Dewey, of his machine for shearing cloth.

This machine consists of a square frame composed of four upright posts 3. 3. high united by four births at top & four towards the bottom in which stands a box to contain the cloth which stands across one of the frame which must be of sufficient width to admit the cloth which is passed out of it to upward over a shearing board & down between two rollers which draw the cloth in and the horizontal blade or knife is placed on the upper side of a board which lies across the frame from birth to birth with the edge brought close to the cloth & when it breaks over the shearing board, it is gauged by springs as is the horizontal blade. Suppose the frame to stand North & South the blade is turned to the North end. The flyer is about from 3 to 6 inches in width & suspended over the other blade by a pivot at each end. said flyer is made with two edges in shape like a couriers knife & twisted so that when one edge is down operating the other has advanced a number of inches. said flyer is turned by a cord band from a wheel of about 8 in. diam. suspended on a shaft which lies across the top of the frame about 3 from the flyer. on the other end of the shaft is a wheel about 3 in. diam. which turns a wheel of equal size with the former which is on the end of one of the before mentioned rollers. The machine is put in motion by the performer who stands at the birth west corner of the frame & turns by a pin in the first mentioned wheel on the upper side of the shearing board which is about 10ⁱⁿ wide, is placed a clasp which goes down upon the cloth in the form of a triangle with the point forward & it spreads the cloth to its full width and delivers it smooth and even to the shears.

The

The two ends of the stalk are cracked together, & is delivered
into the same box out of which it is taken.
